UNITED STATES PATENT OFFICE.

MAX HECKING, OF DORTMUND, PRUSSIA, GERMANY.

FEED-WATER HEATER.

SPECIFICATION forming part of Letters Patent No. 410,517, dated September 3, 1889.

Application filed April 24, 1889. Serial No. 308,386. (No model.)

To all whom it may concern:

Be it known that I, MAX HECKING, a subject of the Emperor of Germany, residing at Dortmund, in the Province of Westphalia, 5 in the Kingdom of Prussia and Empire of Germany, have invented certain new and useful Improvements in Apparatus for Heating and Purifying the Feed-Water of Steam-Boilers; and I do hereby declare that the following is a full, clear, and exact description of the invention, which will enable others skilled in the art to which it appertains to construct and use the same, reference being had to the accompanying drawing, which is 10 a perspective isometric view of my apparatus, with some of the parts broken away to show the interior construction.

My invention relates to devices or apparatus for feeding water to steam-boilers of that 15 class which are provided with means for purifying the feed-water before it is fed into the boiler, so as to avoid undue sediment in the boiler, and has for its object to so construct an apparatus of that class as to utilize the 20 exhaust-steam from the engine for heating the water.

With this object in view my invention consists in the detailed construction and combination of parts of the feed-water heating and 25 purifying apparatus, which will be hereinafter more fully described and claimed.

Reference being had to the accompanying drawing, the letter B denotes the well or reservoir from which the feed-water is drawn in 30 the first instance through the suction-pipe a, which connects with the pump p through the valve d', having a three-way cock d² and short connecting-pipe d. The valve-cock d² being adjusted, as illustrated on the drawing, the 35 feed-water is pumped in the direction of the arrows, through pipe b and the air-compressing chamber W, into the spraying-pipe b', which is provided with a rose b² at its upper end, projecting into the lower part of the 40 open-mouthed drum or cylinder D. The latter is mounted upon and forms an upward extension of a closed tank or receiver R, which is placed at a suitable elevation upon a scaffold or supporting-frame C. This tank R is 45 provided on one side near its top with a faucet u, and in the top with the escape pipe or funnel c.

Projecting through one side of tank R is a pipe E, having an enlargement or chamber O, in the top of which is fastened a vertical 55 tube F, of glass, or of metal with a glass strip or window running its entire length and open at the top. Chamber O connects, by a pipe G having a valve g, with the bottom of a second tank or reservoir R', having a faucet f, 60 and provided near its bottom with the pipe e, leading to and communicating with the pump p', from which another pipe h' leads to the boiler.

The mouth or upper end of the cylindrical 65 drum or extension D may be closed by means of a valve i, and is provided with a pipe j, open at its outer end and having a branch pipe k, which communicates with the exhaust-ports of the engine. At the junction of these 70 pipes j and k is a three-way valve l.

Having in the foregoing described in detail the construction of the apparatus, I shall now proceed to describe its operation, which is as follows: The valve i in the top of drum 75 D having been closed and the three-way valve l adjusted, as shown in the drawing—i.e., closing the outlet-pipe j and opening communication between the steam-pipe k and the drum—steam will enter the drum D and 80 at the same time pump p is set working, which pumps water (valve-cock d² being first properly set or adjusted) from the reservoir B into the lower end of the drum or cylinder, delivering the same through the sprayer or 85 rose b² in the form of a fine continuous spray. Meeting the jet of steam from pipe k, (indicated by the arrow,) the spray is thoroughly heated and projected to the bottom of tank R, the excess of steam which has not been 90 condensed by the spray passing off through pipe c.

The level of the hot water in tank R may be ascertained by means of the gage-glass F, and should the tank become too full the excess of water may be drawn off through the faucet u.

The hot water in tank R escapes through pipe E, chamber O, and pipe G into the sediment-collecting tank R', (valve g being open,) 100

from which the mud or fluid sediment may be drawn off through faucet *f*, while the clear feed-water is fed to the boiler through pump *p'* and pipe *h'*.

5 The steam for operating the feed-pump *p'* is supplied from the boiler through pipe *h*.

If it is desired to reheat the water in tank *R* before feeding it to the secondary tank *R'* and the boiler, then this may be accomplished in a simple and expeditious manner by closing valve *g* in pipe *G* and so adjusting valve *d'* as to shut off connection with pipe *a*, but open it with pipe *m*, which results in pump *p* circulating the water for any desired length of time from tank *R* through pipe *E*, chamber *O*, pipe *m*, with its connecting part or branch of pipe *G*, valve *d'*, pipe *d*, pump *p*, and pipe *b b'* into the cylinder or dome *D* and back to tank *R*. The feed-water having been heated in this manner to the proper degree of temperature, valves *d'* and *g* are readjusted, and the feed-water is now drawn from tank *R* into the sediment or secondary tank *R'*, ready to be fed to the boiler.

By heating the feed-water in the dome *D* in the form of a finely-communited spray, the impurities in the water are projected in great part in the form of sediment into the bottom of tank *R* below the outlet *E*, and may be drawn off at suitable intervals through the bottom pipe *v*. Such finer particles as are not projected to the bottom of this tank, but pass with the feed-water through pipe *G*, will settle in the secondary tank *R'*, as already described, before the feed-water reaches the boiler.

By opening the valve *i* in the top of the

drum a certain amount of atmospheric air may be admitted into the same, whereby I find that the separation of impurities from the feed-water spray is facilitated, the valve being so arranged as to deflect the jet of steam in a downward direction.

If the steam-pressure in pipe *k* becomes too great, it may be relieved by partly opening the valve *l*, which permits a portion of the steam to escape out into the open air through the branch pipe *j*.

If desired, suitable chemicals for purifying the water may also be placed in the well or reservoir *B*.

Having thus described my invention, I claim and desire to secure by Letters Patent of the United States—

The herein-described apparatus for heating and purifying the feed-water for steam-boilers, consisting of the following combined and co-operative parts, viz: tank *R*, having pipes *c* and *v* and faucet *u*, heating-dome *D*, having valve *i* and branched pipe *j k*, provided with the valve *l*, water-pipe *b b'*, having air-chamber *W* and rose or spraying nozzle *b²*, discharge-pipe *E G*, having gage-chamber *O*, provided with the gage-glass *F* and valve *g*, secondary or sediment tank *R'*, connecting-pipe *e*, feed-pump *p'*, suction-pipe *a*, valve *d'*, having three-way cock *d²*, connecting-pipe *d*, pump *p*, and branch pipe *m*, all constructed and combined to operate substantially in the manner and for the purpose herein set forth.

MAX HECKING.
